UNITED STATES PATENT OFFICE.

FREDERICK W. BALSTER, OF WILMINGTON, DELAWARE.

BURNER.

1,418,422.

Specification of Letters Patent. Patented June 6, 1922.

Application filed October 23, 1920. Serial No. 418,873.

To all whom it may concern:

Be it known that I, FREDERICK W. BALSTER, a citizen of the United States, residing in Wilmington, Delaware, have invented 5 certain Improvements in Burners, of which the following is a specification.

My invention relates to certain improvements in burners for liquid fuel and more particularly burners employed for boilers of 10 steam automobiles, auto trucks, tractors, and the like.

One object of my invention is to provide an improved structure in which the flame will be distributed evenly over the entire 15 surface of the burner.

A further object of the invention is to simplify the construction.

Still another object of the invention is to provide means whereby the liquid fuel is 20 brought to the proper temperature before being admitted to the burner.

Another object of the invention is to provide a suitable fuel diffuser, which forms a mixing chamber for the gasified fuel and 25 to provide a porous straining medium through which the fuel must pass on the way to the gasifying means.

The invention also relates to other details, which will be fully described herein- 30 after, reference being had to the accompanying drawings, in which:

Fig. 1 is a sectional view of an automobile steam boiler chamber illustrating my improved burner;

35 Fig. 2 is a transverse sectional view on the line 2—2, Fig. 1;

Fig. 3 is a sectional plan view on the line 3—3, Fig. 1, showing the burner;

40 Fig. 4 is an enlarged view of a portion of the rear wall illustrating the straining medium;

Fig. 5 is a sectional view of the delivery nozzle;

45 Fig. 6 is a sectional view on the line 6—6, Fig. 5;

Fig. 7 is a perspective view of the deflector;

Fig. 8 is a sectional view of one of the pilot burners; and

50 Fig. 9 is a plan view of Fig. 8.

Referring to the drawings, 1 is the boiler casing made as illustrated in Figs. 1 and 2. 2 is the boiler of any suitable construction. 3 is the back flue separated from the combustion chamber 4 by a back wall 5. In

this back wall is the generating chamber 6 described hereinafter. 7 is the burner, which extends over the entire surface of the 60 combustion chamber below the boiler.

8 is a vaporizing tube extending longitudinally of the combustion chamber and in this vaporizing tube is a rod 9 having a spiral groove therein forming a spiral duct 65 for the liquid fuel so that by the time the fuel reaches the pipe 10, connected with the delivery nozzle 11, it is properly vaporized to be projected into the mixing chamber 12. The generating chamber is formed in the 70 back wall 5 by cutting out the back wall and inserting a plate 13 therein, as shown in Fig. 4. The two walls are joined to form the generating chamber 6. This chamber is enlarged by a series of transverse openings 75 extending from side to side of the boiler casting and closed by screw plugs 14. Located in these openings are rods 15 of alundum, or any highly porous refractory material through which the fluid must pass. These 80 rods can be readily removed and replaced, when necessary.

The plate 13 is extended up beyond the lower end of the boiler and in contact therewith as shown in Fig. 1, so that it will retain 85 the heat after the burner flame is extinguished, and this construction also prevents the back plate from being overheated.

16 is the fluid pipe communicating with the generating chamber 6. 17 is a pipe, 90 which forms communication between the upper end of the generating chamber 6 and the rear end of the vaporizing tube 8, as shown clearly in Fig. 1. This generating tube is also connected by a pipe 18 with the steam 95 pipe 19 at the boiler. In this pipe 18 is a valve 20 so that, when necessary, the valve 20 can be opened and steam under pressure can be blown through the vaporizing tube.

21 is a mud drum connected by pipes 22 with the boiler. 23 is the water inlet pipe. The pipes 17 and 22, as well as the mud drum, are located at the lower end of the flue 3.

The burner is made as shown in Fig. 3 and has a series of diagonal channels 24 radiating from the center line of the boiler towards the sides. These channels form ribs 25, which are perforated, as shown, by numerous fine holes in order to form openings for the escape of gas generated under the burner so that the entire area, directly above the burner, is a mass of flame. The channels 24

are packed with a suitable non-conducting material.

At the forward end of the burner structure is a mixing tube 12, which is bifurcated, 5 forming two channels 12^a leading on each side of the burner towards the rear end, as shown in Fig. 3. This mixing tube discharges the gas under a deflector 26, made in two parts, as shown in Fig. 7, one part being 10 at one side of the center at the rear and the other at the opposite side. In the upper surface of the deflector are diagonal channels 27, tapered as shown. Directly under the rear end of the burner at the center is a 15 pocket 28 with which the channels communicate, forming a final mixing chamber for the fuel that is discharged at the rear of the burner. The mixing tube is turned up at the front, as at 12^b, to form an intake for 20 air above the combustion chamber.

The delivery nozzle is made as shown in Figs. 5 and 6. Screwed into the end of the nozzle casing 11 is a tube 29, which extends into the front wall of the mixing tube and 25 extending through this tube is a needle valve 30, which regulates the flow of fuel to the mixing tube. The needle valve 30 is guided in the nozzle by lateral arms 31, as shown in Fig. 6.

30 In order to separate the products of combustion escaping through the two arms of the mixing tube, a central partition 38 is provided, which extends from the crotch of the tube to the rear wall of the burner.

35 The two pilot openings 32 are formed in this partition. The pilot burners 33 are located in the openings 32 in the partition 38, as clearly shown in Fig. 1. In each burner 33 is a gas passage 34.

40 35 is an electric wire passing through an insulated sleeve in the burner and connected to an igniting wire 36 above the burner screen 37 so that, when a current of electricity is passed through the wire it becomes hot 45 and ignites the gas flowing through the burner. These pilot burners are connected to the fuel supply pipe in any suitable manner.

The burner structure is carried by a suitable metallic casing 39 in which are the 50 side linings 40 of the combustion chamber. This casing extends laterally, as shown in Fig. 2, so as to be carried by the frame of an automobile. The boiler structure is mounted 55 on this lateral extension, as clearly shown in Fig. 2. This construction may be modified considerably without departing from the essential features of the invention.

The mixing tube proper 12 extends to 60 the front edge of the burner structure, as shown in Fig. 1, and the tubular extension 12^b is coupled to it in any suitable manner, this extension reduces the noise due to the drawing in of air.

65 It will be seen by the above construction

that I am enabled to make a burner particularly adapted for use in connection with the boiler of a steam automobile so that the flame will be distributed evenly over the entire burner surface, which extends under 70 the boiler, and that the fuel is thoroughly vaporized before it reaches the mixing tube under the burner. The mixture escapes through the bifurcated tube under the deflecting plate so as to cause the mixture to 75 pass to the rear of the burner and then forward through the diagonal channels 27 in order to distribute the fuel thoroughly before it is ignited at the burner. At the rear of the burner, midway between the sides 80 is the pocket 28 forming a mixing chamber, which communicated with the channels 27 so as to distribute the gases that concentrate at this point. By placing a partition on the center line of the burner 85 from the crotch of the mixing tube to the rear plate, the gases from one arm of the tube are prevented from mixing with the gases from the other arm until they are mixed at a point forward of the central 90 partition.

It will be understood that the fuel is carried inside of the furnace structure rather than on the outside and the air is slightly preheated before it combines with the gas 95 escaping from the nozzle.

I claim:—

1. The combination in a burner structure, of a combustion chamber; a boiler located above the combustion chamber; a perforated 100 plate extending under the combustion chamber and forming a burner; a central, longitudinal partition extending part-way through the length of the chamber under the burner; a bifurcated mixing tube, the arms of which 105 extend on either side of the partition; a deflecting plate for preventing the direct flow of fuel from the mixing chamber to the burner openings above the tube; and a nozzle for the vaporized fuel located in the 110 mixing tube.

2. The combination in a burner structure, of a plate having a series of channels spaced apart and forming ribs; channels under the ribs, said ribs being perforated; a bifurcated 115 mixing tube; and a deflector above the discharge end of the mixing tube so as to cause the fuel to pass indirectly to the burner openings.

3. The combination in a burner structure, of a perforated plate; a chamber under the plate; a mixing tube having a central portion and two arms; a central partition extending between the arms; and a deflector located below the perforated plate at the rear 125 end and having diagonal passages therein so that the fuel, as it escapes from the mixing tube, will be deflected and distributed in order to produce an even flame over the entire burner surface.

4. The combination in a burner structure, of a plate having a series of spaced diagonal grooves in its upper surface; ribs between the grooves, said ribs being perforated for 5 the passage of gas; non-conducting material located in the grooves; a mixing chamber; a central mixing tube; bifurcated so as to extend on each side of the partition; a nozzle located in the mixing tube; a vaporizing 10 tube with which the nozzle communicates; and a deflector above the bifurcated portions of the mixing tube having diagonal tapered channels therein, the parts being so arranged that the gases, as they are discharged into 15 the mixing tube, will be deflected before passing through the openings in the burner plate.

5. The combination of a burner plate having a series of diagonal grooves and ribs, the 20 ribs being perforated and the grooves being filled with a non-conducting material; a bifurcated mixing tube; a fuel nozzle extending into the tube; a deflecting plate; a central partition; an opening in the central partition; and a pilot burner located in the 25 opening.

6. The combination of a perforated burner plate; a mixing chamber under the plate; a mixing tube communicating with the chamber; a fuel nozzle extending into the tube; and a vaporizing tube extending above the burner plate and having a spiral passage 30 therein, one end of the vaporizing tube being connected to the fuel supply pipe and the 35 other end being connected with the nozzle.

7. The combination in a burner structure,

of a chamber having fire-resisting walls; a burner structure in the bottom of the chamber, one of the walls having a generating passage into which the fuel is delivered; a 40 body of porous, refractory material in said passage through which the fuel passes, said material serving to strain the fuel and to impart heat thereto; a vaporizing pipe mounted above the burner and connected to 45 said chamber; and a nozzle for delivering fuel in a vaporized condition to the burner.

8. The combination in a burner structure, of a chamber; a burner located at the bottom of the chamber, one of the walls of the chamber having a generating passage therein; a transverse cavity communicating with the passage; a rod of porous, refractory material in the cavity, said cavity being open at one or both ends for the withdrawal or replacement of the rod; a vaporizing pipe communicating with the passage in the wall; and a nozzle connected to the pipe. 50

9. The combination of a burner consisting of a perforated plate; a mixing chamber under the plate; a mixing tube communicating with the chamber; a deflector for distributing fuel under the plate; a nozzle; a vaporizing tube extending above the burner and connected to the nozzle; a generating passage; 60 a pipe forming communication between the passage and the vaporizing tube; a steam boiler located above the burner; a steam pipe; and a pipe leading from the steam pipe to the vaporizing tube and having a valve 65 therein. 70
